UNITED STATES PATENT OFFICE.

GEORGE H. CLARK AND LEWIS A. REARDON, OF BOSTON, MASSACHUSETTS.

MACHINE FOR FORMING UPPERS FOR BOOTS OR SHOES.

Application filed May 21, 1923. Serial No. 640,390.

This invention relates to machines for forming uppers for boot, shoes and the like and more particularly to forming uppers for the well known "stitch down" shoe.

Among the objects of the present invention is to produce a machine of this class that may be power operated and which is of such construction and arrangement that certain functions thereof may be performed by power while others may be performed manually or by foot power if desired.

It is a further object of the invention to so arrange the driving mechanism that the machine may be operated in two stages, wherein the first stage accomplishes the functions of clamping and forming the upper and retaining the material in said clamped and formed condition by the respective implements therefor; and the second stage to thereafter restore the clamping and forming implements to their normal or starting positions, between which stages an interval of whatever duration may intervene.

Another object of the invention is to produce a machine of this class wherein the upper is formed from a blank which has been previously cut the desired size and shape, and which when formed and assembled with the sole requires no further trimming. It is therefore an object of this invention to produce a formed shoe upper which, in so far as edge trimming is concerned, is a finished article, and as an aid to said result, the present machine is provided with devices which position the upper prior to the clamping and forming operations and ensure a uniformity of width of flange not heretofore obtainable in machines of this class.

A still further object of the invention is to provide means for heating the upper during the forming process, this being of particular advantage when an upper having a box toe is to be formed or when the material has been previously treated by steaming, moistening, or other well known or usual process.

The invention further contemplates certain other objects such as the production of a heated clamping member which is detachable, and reversible for rights and lefts, and a coacting clamp member and forming plate also detachable and reversible for rights and lefts.

The production of a combined clamp and upper forming plate being capable of universal movement while under pressure is also

an object of the invention, together with the production of certain devices for adjusting the said plate toward or from the forming implement, as well as resilient means coacting with the heated clamp member.

It is not known that the objects above set forth have been attained in an organized machine of this class and therefore it is not the intention to limit this invention to the precise construction and arrangement shown as it is obvious various changes might be made therein without departing from its spirit and scope.

Of the drawings:

Figure 1 represents in side elevation one form of machine embodying the invention, certain portions being broken away to more clearly illustrate portions of the starting and stopping devices.

Figure 2 a view looking toward the right Figure 1.

Figure 3 a view looking toward the left Figure 1.

Figures 4 and 5 details to be referred to.

Figure 6 a top plan view of the machine as seen in Figure 1 certain portions being broken away for clearness.

Figure 7 a top plan view of a portion of the machine seen in Figure 2 showing the coacting clamp and upper forming plate.

Figure 8 a section on the line 8—8, Figure 2 through certain portions of the forward end of the machine showing the material in place and ready for the clamping and forming operations.

Figure 9 a view similar to Figure 8 but showing the material as having been formed and in close contact with the heating devices.

Figure 10 in perspective view shows a blank as it would appear when removed from the machine.

Figure 11 a view similar to Figure 10 but showing the reverse side of the formed blank.

Like characters represent like parts throughout the several figures of the drawings.

Referring to the drawings:

The drawings herewith illustrate one form of machine embodying the present invention and consists in part of a suitable frame 10 having adjustably supported thereon a box-like structure 11 secured to the frame 10 by the screws 12 and capable of vertical adjustment through the cooperation

of the wedge members 13 affixed to the said box 11 and the slidable wedge members 14 under the control of the screw 15. By slackening the screws 12 and turning the screw 15 in the proper direction it is obvious that the vertical position of the box 11 and the parts carried thereby may be changed to a nicety to accommodate the class of material to be operated upon.

10 The box 11 is so constructed as to removably support a combined clamp cooperating and upper forming plate 16 which will be hereinafter referred to as the forming plate.

15 The said forming plate 16 may be made of metal, but it is preferred that it shall be composed of wood, fibre board or similar material of sufficient strength to stand the pressure ordinarily applied to it.

20 Three of the edges of the said plate have inserted in them resilient extensions 17 which snugly but removably fit into the depression 18 formed by the side walls 19 of the box 11 and the inwardly extended shelf 20 which indirectly supports the said plate 16.

25 The said shelf 20 is in turn provided with suitable holes or depressions which are adapted to receive resilient upstanding members such as rubber plugs 21 upon which it is intended to support the plate 16.

30 It will be readily seen that the plate 16 is mounted in the box 11 in such manner that it is susceptible to yielding movement in four directions as circumstances call upon it to be so, and may be said to be a universally movable plate and will be referred to as such hereinafter.

35 Located within the box 11 and with its upper portion preferably in contact with or at least in close proximity to the said plate 16, is a heating medium 25, which is resilient in nature and is slightly concaved at the top side to receive and snugly contact with a formed upper blank, and is hollow to receive steam, hot air or hot water through the entrance and exit pipes 26 and 27 respectively.

40 It will be obvious that it is within the limits of the invention to heat the medium 25 by means other than the aforementioned, as for instance by electricity if so desired.

45 In order to insure uniformity of upper flange or in other words to properly position the upper blank relatively to the forming plate 16 a plurality of gauge pins 28 are provided, which are adjustable on the said plate by means of the screws 29, the said plate having slots 30 through which the 50 perpendicularly arranged cross members 31 extend so that the same pins will function as gauges when the plate is reversed.

55 The clamp member 32 which is also a feature of the invention is mounted in a universal manner and is arranged to be heated in the present instance by electricity.

While it is desired to operate the clamp 32 by cam movement it is also desired that means be employed to compensate for slight unforeseen changes in thickness of the material fed to the machine.

70 Fast in the frame 10 is a stud 35 upon which the levers 36 are loosely mounted, the forward ends of which are slotted as at 37 to receive the spherical studs 38 laterally extending from the clamp 32 see Figure 4. 75 Springs 39 fast with said levers normally retain said clamp in operative position and yet permit of the reversal or replacement of said clamp.

80 A heating unit 40 for the said clamp may be used which is preferably of a well known electric type deriving its power from any suitable source. The rear portions of the said levers 36 are in the present instance composed of spring metal parts 41 suitably secured to the levers 36 and having cam rollers 42 adapted to contact with the cams 43 on the crank shaft 44 under the action of springs 45.

85 It will be readily seen that if, by accident or otherwise, material of a thickness greater than intended should be fed to the machine, the positive action of the cams 43 would be sufficiently relieved by the yielding movements of the spring parts 41, so that breakage would not take place and the material would not be unduly clamped to the detriment thereof or the proper forming of the upper blank interfered with.

90 The upper forming implement 50 shown in the present instance as the toe part of a last, but which if desired may be a full last as seen in Figure 5, is suitably secured, in a removable manner to the plunger 51 95 guided in bearings 52 of the frame 10 and held from turning therein by the spline 53 and groove 54 of said plunger 51.

100 The plunger actuating lever 55 has a bifurcated transversely slotted end 56 adapted to embrace the roller studs 57 at the upper end of said plunger while its rear end is connected by the link 58 with the crank 59 of the shaft 44.

105 The said lever 55 is pivotally mounted on a shaft 60 the bearings of which are slid- 110 able boxes 61 suitably guided in ways 62 of an upstanding portion 63 of the frame 10.

115 Springs 64 interposed between the said boxes 61 and caps 65, and under the control of thumb screws 66, are provided. Hold down latches 67 for the boxes 61, the purpose of which will be hereinafter referred to, are also provided.

120 The crank shaft 44 has fast therewith a gear 70 in mesh with a smaller gear 71 the ratio between the two in the present instance being two to one.

125 The said gear 71 is loose on the stud shaft 72 and has as a part thereof a hub 73 in 130 which is slidably mounted a stud 74 be-

hind which is a spring 75 normally tending to force the said stud 74 outwardly.

The stud 74 has a pin 76 extending therefrom which travels in a slot longitudinally 5 of said hub and is adapted to be engaged by a stud retracting brake shoe 77 at the end of a rod 78 which is normally held in the position shown in Figure 1 by a spring 79.

10 Also loose on the said stud shaft 72 is a preferably continuously rotating pulley 80 extending from the hub of which is a dog 81 adapted to at times engage the stud 74 and through the gears 71 and 70 drive the ma- 15 chine.

The rod 78 may be manually operated or if desired may be operated by foot power.

Loosely attached to the shaft 60 is a yoke 20 85 having rod connection 86 with a hand or foot operated lever not shown, the purpose of which will be more fully explained.

In operating the machine let it be supposed that the proper setting of the machine for the reception of the material to be operated upon has been made and that the said 25 material is of such nature that the forming operation may be completed entirely by power.

In the latter case the latches 67 will be 30 engaged with the boxes 61 and the machine ready for use.

The blank B will be placed on the plate 16 see Figure 8 where it will be positioned by the gauge members 31, whereupon the 35 rod 78 will be depressed, releasing the pin 76, by which action the stud 74 is forced into the path of the continuously revolving dog 81, which contacts therewith and causes the machine to start.

40 As it is in many instances advisable to continue the pressure of the forming implement 50 upon the material for an indefinite period the present machine is designed to operate in two stages if necessary and for 45 that reason after tripping the stud 74, the rod 78 will be allowed to resume its normal position ready for the shoe 77 to engage the pin 76 and force the stud 74 out of engagement with the dog 81, which will occur upon 50 one complete revolution of the gear 71 or one half revolution of the gear 70 and consequently of the cam 43 and crank 59.

When the machine has been started as 55 previously described, the cams 43 will cause the clamp 32 to descend and clamp the material between it and the plate 16 meanwhile the forming implement 50 has started on its way toward the blank and will continue until it reaches it and forces it gently but 60 firmly into the positions shown in Figure 9 at which time and position the machine will stop as previously explained.

The interval of rest may be long or short 65 according to the judgment of the operator, who will at the proper time, again trip the

stud 74 and cause the machine to resume its normal or starting position whereupon the formed upper will be removed and a new blank inserted for operation.

If the blanks should vary in thickness, or 70 if an individual blank should not be uniform in thickness the proper clamping thereof will not be hindered, as it will be understood that the novel manner of mounting the clamp 32 and the flexible connection between the cams 43 and clamp each of which will do its part in causing automatic adjustment to be made to compensate for the said inequalities of the material. So too 75 the novel manner of supporting the forming plate 16 enables it to be depressed slightly in a plane parallel to itself, or if required tilted in the direction required to thereby relieve undue pressure where not required and it may also be slightly shifted in its 80 own plane automatically upon the descent of the implement to adjust itself to any inequalities of the material or to inaccurate registering of the implement 50 and the shaped slot of the forming plate 16. 85

In order to properly stop the machine on the completion of the second stage of the operation, a stop 90 is provided on the hub 73 which is adapted to meet the end 91 of the shoe 77 after the stud 74 has been retracted and at which time the shoe will function as a brake on the said hub 73. 90

It will be understood however that it is not intended that the machine shall be run at great speed and consequently the braking 100 and stopping actions are accomplished without detrimental shock.

In the event that a class of material is to be operated upon that is tender, or that is of such nature that it is not advisable to attempt to completely form it in a power driven machine, provision has been made to perform part of the operation by power and the delicate portion by hand or foot power. 105

In the last mentioned instance the latches 67 will be disengaged from the boxes 61 and the resistance of the springs 64 regulated by the screws 66 in such manner that when the machine is started the clamping will take place as before, and the implement 50 will descend to engage the material, but will not positively force it for its full distance. It will however be forced to meet the material and start it on its forming 115 operation until the resistance of the material overcomes that of the springs 64, at which time the implement will not appreciably descend further under power but the pivotal shaft 60 will be raised instead, until the machine comes to a stop at the end of the first stage. 120

At this time the upper is not fully formed and in fact may not be more than started 125 and to complete the operation, the shaft 60 130

has a yoke 85 having rod 86 connection with a hand, or foot lever, not shown which will now be depressed, gradually, if need be, and as many times as necessary, until the material is finally worked to a point where the upper is formed, and if desired the latches 67 may be engaged with the box 61 and the formed upper allowed to set for a while under pressure.

19 At the proper time in the judgment of the operator the machine will be again started on its second stage and the formed upper removed to make place for another blank.

15 It will be readily understood that the springs 64 may be of such size and the tension thereof regulated to such extent that very delicate material may be operated upon, in fact equaling that of a full, hand 20 machine, while on this same machine sturdy material may be formed entirely by the power process.

In either of the above methods of operation the upper blank will be gradually forced downwardly into form and on its way will contact with the heating medium 25 which will closely contact with the material and aid in its formation by the transmission of heat thereto.

30 To further facilitate in the forming of the upper, the forming implement 50 will be heated in any well known manner, but preferably by electricity as indicated by the wires 50* which convey the current thereto 35 from any suitable source.

Having described the invention we claim:—

1. In a power operated upper forming machine in combination, a forming implement a forming plate; means to adjust said plate toward and from said forming implement; means whereby said plate may be shifted in its own plane; means whereby said plate may be depressed to thereby afford universal movement thereof; a clamp member adapted to coact with said plate to clamp the work, and mounted so as to be tilted in a universal manner; means to actuate said clamp member; resilient means intermediate said clamp member and said actuator; and means to actuate said forming implement.

2. In a power operated upper forming machine, in combination, a forming implement a universally movable forming plate; means to adjust said plate relatively to said forming implement; a universally movable clamp member; means to actuate said clamp member; resilient means interposed between said clamp member and said actuator; means to actuate said forming implement; and means to complete a cycle of operations of said machine in a plurality of stages.

3. A power operated upper forming machine of the class described having in combination, a forming plate; a clamp member; means whereby said clamp member may be tilted in one direction; carriers for said clamp member adapted to be independently moved at times whereby said clamp member may be tilted in other directions, said carriers having means forming part thereof adapted to yield under certain work clamping conditions; means to actuate said carriers to clamp the work; a forming implement; and means to actuate said implement.

4. In a machine for forming uppers for boots and shoes and capable of being both power and manually operated, a forming plate; work clamp means coacting therewith; a forming implement; power operated means, including a lever, for actuating said implement, said lever being normally fulcrumed at a given point; means whereby said lever may fulcrum at another point; and means whereby said lever may be caused to fulcrum at a third point.

5. In a machine for forming uppers for boots and shoes, and capable of being both power and manually operated, a forming plate; work clamp means coacting therewith; a forming implement; power operated means arranged to actuate said implement to form an upper but to yield before the complete forming thereof if called upon to do so by the resistance of said upper, and while the machine is under power; and means to thereafter complete the formation of an upper, manually.

Signed by us at Boston, Massachusetts this 3rd day of May 1923.

GEORGE H. CLARK.
